UNITED STATES PATENT OFFICE.

LEMUEL B. DECKER, OF KENOGAMI, QUEBEC, CANADA.

PAPER-STOCK REGULATOR.

1,423,555.

Specification of Letters Patent. Patented July 25, 1922.

Application filed January 27, 1921. Serial No. 440,465.

To all whom it may concern:

Be it known that I, LEMUEL B. DECKER, a citizen of the United States, residing at Kenogami, Province of Quebec, Canada, 5 have invented certain new and useful Improvements in Paper-Stock Regulators; and I do hereby declare that the following is a full, clear, and exact description of the invention, such as will enable others skilled in 10 the art to which it appertains to make and use the same.

The present invention relates to paper stock regulators and more particularly to a contrivance for securing the consistency 15 of groundwood and sulphite stock used in the manufacture of paper, this constituting one of the important objects of the invention.

Another object of the same is to provide 20 a device whereby the percentage and mixture of the paper stock may be adequately regulated and controlled, according to requirements, as well as the consistency of same.

25 A further object of the invention is in the provision of an apparatus that does away with all beaters, jordans, beater tanks and jordan tanks, and, all power and equipment needed to run same.

30 Another object of the same invention is to set forth a contrivance whose main function is to produce a continuous mixture of groundwood and sulphite at a regularly defined consistency and percentage, thereby increasing the production and efficiency of 35 the paper machine.

With the above and other objects in view which may appear as inherently related with the nature and scope of the present invention, reference is now to be had, for the purpose of disclosing same, to the hereunto annexed drawings forming an integral part of the specification, and, wherein the various parts being designated by numerals are referred to throughout the description by the 45 same corresponding characters.

Of the above referred to drawings:—

Figure 1 is a side elevation of the apparatus embodying the present invention;

50 Figure 2 is also a side elevation, enlarged, of a part of the invention showing its connection with the baffle mixer;

Figure 3 is a section in elevation of the water tank and automatically operated 55 valve;

Figure 4 is a plan view of same;

Figure 5 shows a plan view of the apparatus used in connection with the groundwood stuff box; and,

Figure 6 is a section through line A—B 60 in Figure 2.

Descriptively, and with reference to the above drawings, the groundwood stock is pumped, through pipe 2, into the stuff box 1, which is made of two compartments. This 65 stuff box is concentrically located within another recipient of larger size than the latter, thus forming a peripheral capacity 3 between both which is adapted to receive any overflow of stock coming from the main 70 stuff box 1. An outlet 4 is formed with said peripheral capacity, whereby the overflow of stock may be removed.

A gate 5 is formed in said recipients 1 and 3, and, has an adjustable panel 6 slidably 75 mounted in connection with same for the purpose of controlling the size of the opening through which the stock from the recipient 1 is caused to be discharged on and through a hinged trough 7. This trough 80 member has one of its ends pivotally mounted on a knife edge 8, while the opposite end of same is held in space by means of a draw-bar 9 having its lower end flexibly secured to said trough, as shown at 10, and, its upper 85 end resting, by means of a nut 11, on a scale beam 12. With the nut 11, being in threaded engagement with the upper end of said draw-bar, the slope of the trough 7 may be 90 adjusted according to requirements.

The said scale beam 12 is supported by a frame structure 13 which also supports the pivotable end of said trough, and, is fulcrumed on knife edges 14 suitably secured to the upper portion of said frame structure 13. 95 One end of said scale beam is freely adjusted in a slot formed by the meeting in space relation of the two extremities of the structural frame members 15 secured one end to the main structural framing 13. A 100 longitudinal slot 16 formed in the two parallelly meeting branches of said members 15, engages an adjustable bolt and nut 17, for the purpose of limiting in an adjustable manner the upward motion of the scale 105 beam 12.

A movable weight 18, slidably mounted on the scale beam 12, between the knife edges 14 and the structural frame members 15, provides for the means of regulat- 110

ing, as desired, the weight of the stock material adapted to flow by gravity down through the trough 7.

To the outer free end of the scale beam 12, 5 is secured a chain 19, whose other end is operably connected to the power arm of a lever 20 fulcrumed at point 21 which is formed with a water tank 22, wherein the quantity of water admitted, through pipe 10 23, is automatically regulated by a ball valve 24. Thereby, when the water within said tank has attained a predetermined altitude or level, the ball member 25 of said valve actuates, through a lever 26, the closing of 15 said valve and automatically cuts off the supply of water into said tank.

Suspended from the extremity of the weight arm of the lever 20, is a valve 27, whose seat 28 is located on the inside bottom 20 of said water tank 22. This valve is preferably of hollow cylindrical form, and when closed, as shown in Figure 3, completely recovers the perforated end 29 of the water pipe 30 which projects on the inside 25 side of said water tank. This water pipe 30 leads from the water box 22 to the inlet stock pipe 2 or into the stuff box 1.

Operatively, when the stock from box 1 is heavy coming through gate 5 on to the 30 weighing trough 7 beyond a certain required limit, the said trough, through the draw-bar 9, causes the scale beam to drop down, simultaneously causing the opening of valve 27, when water, from the tank 22, 35 rushing through the perforations 31 formed with the end 29 of pipe 30, immediately leads its way through said pipe 30 into the stuff box 1. The pulp being thereby thinned, the load on the weighing trough 7 40 is subsequently lightened, when the scale beam 12 thereby caused to resume an upward motion, the valve 27 is shifted back tight upon its seat 31, and, the water supply from the tank to the stuff box is automatically 45 cut off.

In this way a uniform consistency of the paper stock is continually and automatically ensured and adapted to be regulated.

The stock on leaving the above described 50 regulator apparatus enters a baffle mixer 32, which is made up of a plurality of cantilever shelves 33 disposed in space relation to each other and alternately secured to the opposing vertical walls of said baffle mixer. 55 Therefrom, the combined sulphite and groundwood stock is lead, through conduit 34, to the pump fan 35, thence to the distributing head 36, from where same is controllably distributed to the paper machine chests 60 through pipes 37, 38, 39 and 40.

The above described procedure is followed both in the case of groundwood and sulphite. In fact, Figure 1 of the drawings shows on the left hand side of the sheet, the 65 apparatus, embodying the present invention,

used in connection with groundwood, while, on the right hand side of the same sheet, substantially the same apparatus is applied with relation to sulphite, the baffle mixer 32 being disposed therebetween so as to receive 70 the discharge from both.

In the accompanying drawings and foregoing description have been shown a simple and preferred form of the invention. It is however understood that no limitation is necessarily made to the precise structural details therein exhibited, but the right is hereby reserved to any changes, alterations or modifications to which recourse may be had that come within the scope of the following claims without departing from the spirit of the invention or sacrificing the efficiency of the same.

Having thus fully described my invention, what I claim as new and desire to secure 85 by Letters-Patent, is:

1. An apparatus of the character herein described, comprising means for automatically regulating the consistency and percentage of groundwood and sulphite stock 90 used in the manufacture of paper.

2. An apparatus of the character herein described, comprising means for producing a continuous mixture of groundwood and sulphite, and, means for automatically regulating the consistency and percentage of same, substantially as described and for the purpose specified.

3. In an apparatus of the character herein described including a groundwood stock box 100 and a sulphite stock box disposed in space relation to and opposite each other, a gate formed with said boxes, an adjustable panel controlling the opening of said gate, an inclined trough hinged one end adjacent to 105 and in communication with said gate opening, means for adjusting the inclination of said trough, means for automatically regulating the consistency and percentage of said groundwood stock and of said sulphite 110 stock prior to its being mixed together, and, means for producing a continuous mixture of said stock and feeding same to the paper making machines, substantially as described and for the purpose specified.

4. In an apparatus of the character herein described including a groundwood stock box and a sulphite stock box disposed in space relation to and opposite to each other, a gate formed with said boxes, an adjustable 115 panel controlling the opening of said gate, an inclined trough hinged one end adjacent to and in communication with said gate opening, a structural frame built in connection with said stock boxes, a scale beam 120 pivotally mounted on said structural frame, an adjustable draw-bar resting one end on said scale beam and supporting in space through opposite end of same the free end of said trough, a water tank, conduit con- 125 130

nections between said water tank and said stock boxes, a valve formed with ends of said connections projecting on the inside of said water tank, said valve operably connected with and adapted to be actuated by said scale beam, and, means for automatically regulating the consistency and per-

centage of said groundwood and sulphite stock prior to its being mixed together, substantially as described and for the purpose 10 specified.

In witness whereof I have hereunto set my hand.

LEMUEL B. DECKER.
